UNITED STATES PATENT OFFICE.

WILLIAM A. PIKE, OF BRIDGEPORT, CONNECTICUT, ASSIGNOR TO BRADLEY A. HARD AND SAMUEL PARSONS, OF NEW YORK, N. Y.

DESIGN FOR NOTE-PAPER.

SPECIFICATION forming part of Design No. 15,010, dated May 20, 1884.

Application filed July 7, 1883. Term of patent 7 years.

To all whom it may concern:

Be it known that I, WILLIAM A. PIKE, a citizen of the United States, residing at Bridgeport, in the county of Fairfield and State of Connecticut, have invented and produced a new and original Design for Note-Paper, of which the following is a specification, reference being had to the accompanying drawing, forming part thereof.

10 The drawing represents a view in perspective, showing the different parts of my design.

15 The leading feature of my design consists of a wedding-bell, A, the lucky or wish bone B, the wedding-ring C, and the cord D, all shown in the drawing, and arranged as follows:

The wedding-bell A being suspended between the open part of the wish-bone B, the golden ring C being placed over and around the closed end of the wish-bone, and the cord D placed 20 through and attached to the ring C, all shown in the drawing.

I claim—

The design for note-paper herein shown and described, the same consisting of the wedding-bell A, the lucky or wish-bone B, the wedding-ring C, and cord D, all arranged substantially as shown and described.

WILLIAM A. PIKE.
